ARTICULATED CAR

Ernest R. Schroeder, Hawthorne, N. J., and Victor Willoughby, Concord, N. H., assignors to American Car and Foundry Company, New York, N. Y., a corporation of New Jersey

Original application October 6, 1941, Serial No. 413,716. Divided and this application September 29, 1944, Serial No. 556,376

10 Claims. (Cl. 105—288)

1

This invention relates to articulated cars in general and in particular to articulated cars for use as mine or other industrial cars of the drop bottom type and is a division of application 413,716, filed October 6, 1941, and issued April 10, 1945, as Patent No. 2,373,348.

In recent years the trend has been toward larger capacity cars for use in mines since so many of the mines are now mechanized and the haul from the loading equipment to the dumping station has become extremely long as the mining progresses. The trend also has been toward cars in which the minimum of dead weight is used which will accordingly permit of the present locomotives hauling more pay material. In mining work the length of the loading room, width of the passageways and curvature of the track, both horizontal and vertical, limits the capacity of individual mine cars. It is an object, therefore, of the present invention to provide a mine car having the maximum capacity possible for a given length car and of a total overall length greater than could normally pass through the mine.

A further object of the invention is the provision of a large capacity mine car carrying substantially twice the material which could be carried by the largest type of car now in use.

A still further object of the invention is the provision of a large capacity mine car in which the ratio of carrying capacity to dead weight has been materially increased.

A yet further object of the invention is the provision of a large capacity mine car of a length materially less than the length of two standard units as now used and in which one set of wheels and axles and couplers has been eliminated.

These and other objects of the invention will be apparent to persons skilled in the art from a study of the following description and accompanying drawings, in which

Figure 1 is an elevational view of the improved car having parts broken away and other parts in section to better disclose the invention;

Fig. 2 is a sectional view taken substantially on line 2—2 of Fig. 1;

Fig. 3 is a sectional view taken substantially on line 3—3 of Fig. 1;

Fig. 4 is a rear end view of the car;

Fig. 5 is a sectional view showing substantially half the car at the end axles;

Fig. 6 is an enlarged side view of the joint between the units forming the car;

Fig. 7 is a sectional view of one of the connections between the car units;

2

Fig. 8 is a sectional view disclosing the side frame construction of one of the units forming the car;

Fig. 9 is a perspective view of the journal box mounting at the center of the car;

Fig. 10 is a side view similar to Fig. 1 but showing a modified form of articulation;

Fig. 11 is a rear end view of the forward unit of the car;

Fig. 12 is a sectional view taken substantially on line 12—12 of Fig. 10, and

Figs. 13 and 14 are side and plan views respectively of the articulation shown in Fig. 10.

Referring now to the drawings in detail, it will be seen that the improvement has been applied to mine cars of the drop bottom type but it will be obvious that the invention could be applied to other types of cars. As clearly shown in the figures, the car is constructed with a forward unit A and a rear unit B, each of which carries at its extreme end couplers C. Also each unit is formed with front and rear end walls 2 and 4 joined to side walls 6 which slope downwardly and inwardly to discharge material through the drop bottom doors D between the track rails (not shown). The end walls and side walls are supported upon an underframe unit which is formed of channel side sills 8, joined together at their outer ends by channel end sills 10. As clearly shown in the figures, the coupler units project into the body of the car and are housed by means of housings 12 fastened to the underframe structure and to the end walls of the car. As is customary in cars of this type the sloping side walls are braced to the underframe by means of gussets 14 and are prevented from spreading by cross ties 16. The car is supported adjacent its front and rear ends upon wheels W rotatably mounted on stub axles 18 which in turn support inner bearings 19 and outer bearings 20 (see Figs. 1, 5 and 10). The bearings support the lower ends of springs 22, the upper ends of which bear in inverted U-shaped elements 24, the inner of which is connected to the channel side frame 8 and the outer of which is connected to a short bulb angle 25 extending between and suitably attached to adjacent gussets 14. The upper portion of the wheel projects into the car body through openings cut in the side floors and in order to carry lading over the wheels and over the inner bearings and spring supports, wheel housings 28 are provided. As is customary with cars of this type, the drop bottom doors D extend between the side sill structures and each rearward door controls the opening of the next forward

door, with the end door being controlled by a latch. As clearly shown in Figs. 2 and 11, the latch for unit A is of more or less standard construction, having an arm 30 pivoted to the car as at 31 and carrying a hook 32 adapted to engage and support the lug 33 fastened on the rear end of the rearmost door of the unit. The latch and arm are urged to door engaging position by spring 34 as is customary. Due to the projection of the coupler housing into the rear of unit B, the latch has of necessity been modified as shown in Fig. 4, which discloses the latch for the rear of unit B. This latch is formed with a bellcrank arm 36 pivoted to the car as at 37 and connected to an adjustable pull rod 38. The inner end of the pull rod is connected to the latch hook 39 pivoted at its upper end to the coupler housing and at its lower end supporting the lug 40 fixed on the rear edge of the rearmost door of unit B. Upward pressure of arm 30 or bellcrank 36 will, of course, release the rearmost doors of the units A and B, thereby permitting dumping of the entire load carried within the units comprising the car. Although the car units have been described as supported adjacent their ends upon stub axles, it will be obvious that the cars could as readily be supported upon through axles if so desired. It will also be obvious to persons skilled in the art that the preceding description applies in general to more or less standard drop bottom cars with the exception of the latch assembly for the rearmost unit.

As clearly shown in the figures, and particularly Fig. 9, it will be seen that the side frames 8 of unit B are of channel formation having the flanges 41 directed horizontally outward and extending to a point substantially flush with the vertical end wall of the car. The ends of the side frame or side sill channels are welded or otherwise secured to inverted U-shaped journal box housings 42. The side arms of the journal box housings are connected together across the car by means of bulb angles 44, having the flanges thereof directed toward each other and secured together. Journal boxes 45 are carried within the journal box housings and resiliently support the car through the medium of springs 48. On the forward side of the forward arm of the journal box housings an open box like structure 50 is secured, having vertical openings 51 formed therein to receive a coupling pin 52 later to be referred to. These box like structures, as well as the upper flanges of the side sill members, are gusseted to the journal box housings by gussets 54. Spreading of the journal box housings is prevented by straps 55 which will also serve to retain the through axle 56 in place and prevent its dropping out of the journal box housings. The axle is supported, as clearly shown, upon wheels 57 located at the center of the car, with the axle in turn supporting the journal boxes 45 between the wheels. As clearly shown in Figs. 6, 7 and 8, the coupling pin 52, previously referred to, passes through the horizontal flanges 58 of a coupling channel 60 adapted to fit between the flanges of the side frame of unit A and slide relative to the side frame upon the flanges. The forward end of the coupling channel has attached thereto a plate 61 pierced to receive a bolt 62, which bolt extends through a hole in a plate 64 welded or otherwise secured to the web and flanges of the side frame channels. Interposed between the plates 61 and 64 is what may be termed a buff spring 65, held in place by the bolt and adapted to resist forward movements of the coupling

channel, while interposed between the plate 64 and the nutted end of the bolt is a spring 66 adapted to resist rearward movements of the coupling channel. Since the coupling channel also must transmit the weight of unit A to the box like structure 50, it is of considerable length and is positively retained within the side frame channels for sliding movement by means of a plate 68 welded or otherwise secured to the flanges of the side frame channels and thereby forming a box-section for reception of the coupling channel.

It will be seen from the preceding description of the articulation arrangement shown in Figs. 1 to 9 inclusive that unit B is supported directly upon a pair of stub axles and one through axle, while unit A is supported directly upon a pair of stub axles and indirectly through the coupling channel upon the centrally located through axle. The units will operate together as a car and can be coupled in train and handled as any other car. When the car is operating on curves the coupling channels 60 will slide in the side frames of unit A to permit such curving with the movement resisted either by springs 65 or 66, dependent upon the side of the car and the direction of the curve. In normal hauling the coupling channel may also slide in the side frame with the haulage strains absorbed by springs 66 and the buffing strains absorbed by springs 65. Although no connection has been shown, it will be obvious that the coupling channel may be greased by any suitable pressure fitting in order to facilitate its movements within the side frame or side channel of unit A.

In the modified articulation shown in Figs. 10 to 14 inclusive the frame of unit B is substantially identical with that just described in connection with Figs. 1 to 9 inclusive and accordingly wherever possible the same reference numerals have been applied. In this form, however, the box like element has been eliminated from the journal box housings and instead spaced plates 70 have been welded or otherwise secured to the journal box housings and pierced at their forward ends to receive pivot pins 72. These pivot pins support swinging hanger links 73, the lower ends of which carry pins 74 extending through a plate 75 positioned parallel to the side frame web and secured to the flanges of the channel, as most clearly shown in Figs. 12, 13 and 14. The upper flange of the side frames of unit A have been cut away, as clearly shown, in order to accommodate the swing links or hangers 73. As clearly shown in Figs. 11 and 13, a small plate 78 is welded or otherwise secured to the web of the side frames of unit A and also to plate 75 inwardly of their ends. In this way a housing is provided for resilient buffers 80, preferably formed of rubber and adapted to strike the forward face of the journal box housing, thereby eliminating metallic contact. Movements of the hangers 73 are controlled by means of rods 82 pivoted to the swing hangers by pins 84. The rods 82 extend through holes in upstanding ears 86 welded or otherwise secured to the journal box housing and to plates 70. The holes in ears 86 are adapted to receive followers 88 spaced apart by springs 90, thus these springs are able to restrict or control horizontal movement of the rod 82 in either direction.

In this modification relative curving between units A and B is accommodated by means of the swing hangers 73, with the swinging movements controlled by springs 90, that is, when the car

goes around a curve one of the hangers will rotate slightly in a clockwise direction about pivot 72, while the other will rotate slightly counterclockwise around its pivot 72. During normal haulage of the cars relative movement between units A and B is accomplished by swinging of the hangers 73 in unison and under control of springs 90. Since buffing strains are usually much greater than haulage strains, excessive buff will be absorbed by the rubber units 80 and transmitted directly through the side frames without overstressing springs 90.

From the preceding description it will be seen that for a given curvature the end and central wheels may be spaced as far apart as it is possible at present to space the axles on a single car. In this way a car of substantially twice the capacity of the largest capacity car now in use on a given curvature in a mine is provided and this car utilizes but one set of couplings. In other words, to carry substantially the same capacity in standard cars would require two cars, thus by constructing the cars as shown and described one set of wheels and axles and one set of couplings is saved. This saving in wheels and axles and couplings is important for at present, particularly with automatic couplings, the cost of automatic couplings is in the neighborhood of one-fourth to one-sixth the total cost of the car. Furthermore, by constructing the cars as shown and described, a substantial saving in length is made, for if two standard cars were to be substituted to carry the same load as the articulated car, the overall length would be much greater than the overall length for the articulated car. This saving in length is important in loading rooms and at dumping stations. Also since one set of wheels and axles and couplers is eliminated, the ratio of useful load to dead weight is materially increased, thereby permitting the present locomotive to haul considerably more useful or pay loads.

Although the invention has been described more or less in detail with specific reference to two modifications thereof, it will be obvious to persons skilled in the art that various other modifications and rearrangements of parts may be made and all such modifications and rearrangements of parts are contemplated as will fall within the scope of the appended claims defining our invention.

What is claimed is:

1. An articulated drop bottom mine car comprising forward and rearward body units, a plurality of drop bottom doors hingedly carried by each body unit, a latch carried by each of said units and controlling the doors of the respective unit, and a plurality of sets of wheels and axles supporting said car and located adjacent the center and each end thereof.

2. An articulated drop bottom mine car comprising forward and rearward body units, couplers attached to the forward and rearward end of the car and protected by coupler housings, a plurality of drop bottom doors hingedly carried by each body unit, a latch carried by the forward unit, a latch suspended from the coupler housing of the rearward unit, said latches controlling the doors of their respective units, and a plurality of sets of wheels and axles supporting said car and located adjacent the center and each end thereof.

3. A drop bottom mine car comprising at least in part, an underframe, a body supported on the underframe, wheel and axle assemblies supporting the underframe and body, a coupler con-

nected to the car and substantially enclosed by said body, a housing over said coupler and attached to the body, a plurality of drop bottom doors closing the bottom of the body, and a latch carried by the coupler housing located wholly within the structural limits of said car and controlling the drop bottom doors.

4. A drop bottom mine car comprising at least in part, an underframe, a body supported on the underframe and having the bottom closed by drop bottom doors, wheel and axle assemblies directly supporting one end of said underframe and body, a wheel and axle assembly indirectly supporting the other end of said underframe and body through slideable means resiliently connected to the underframe and permitting relative longitudinal movement thereof.

5. A mine car comprising in part, an underframe, a lading retaining body supported on the underframe, a wheel and axle assembly directly supporting one end of said underframe and body, a wheel and axle assembly indirectly supporting the other end of said underframe and body through hanger means pivotally connected at one end to the underframe and resiliently connected at the other end to said wheel and axle assembly whereby said underframe may move longitudinally relative to said second named assembly.

6. A mine car comprising in part, an underframe, a lading retaining body supported on the underframe, a first wheel and axle assembly supporting one end of said underframe and body and preventing all but vertical movements therebetween, a second wheel and axle assembly adjacent the other end of said underframe, and means slidably connecting said underframe and said second wheel and axle assembly for relative longitudinal movement, and additional means for resiliently controlling said relative longitudinal movement.

7. An articulated drop bottom mine car comprising forward and rearward body units, a plurality of drop bottom doors hingedly carried by each body unit, a plurality of latches with one carried by each of said units and controlling the doors of the respective unit, and three sets of wheels and axles supporting said car and positioned with one adjacent each end of the car and one adjacent the center thereof.

8. An articulated drop bottom mine car comprising forward and rearward body units, a plurality of drop bottom doors hingedly carried by each body unit, a plurality of latches with one carried by each of said units and controlling the doors of the respective unit, and three sets of wheels and axles supporting said car, two of said sets supporting the outer ends of said body units and the remaining set supporting the inner end of at least one of said units.

9. An articulated mine car comprising forward and rearward body units, couplers resiliently attached to the forward and rearward ends of the car, a plurality of sets of wheels and axles located with one set adjacent the outer end of each body unit and the remaining set adjacent the inner ends thereof, and means resiliently connecting said body units together for relative longitudinal movements.

10. A drop bottom mine car comprising at least in part, an underframe, a body supported on the underframe, wheel and axle assemblies supporting the underframe and body, a coupler connected to the car, a housing for said coupler projecting into said body and attached thereto, a plurality of drop bottom doors for closing the

bottom of the body, and a latch carried by the projecting portion of said coupler housing and controlling said drop bottom doors.
